DESIGN FOR A COAT

Max L. Romer, New York, N. Y.

Application July 7, 1938, Serial No. 78,327

Term of patent 3½ years

To all whom it may concern:

Be it known that I, Max L. Romer, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein—

I claim:

The ornamental design for a coat, substantially as shown.

MAX L. ROMER.
